YARN-WINDING MACHINE

Charles Marsden, Bombay, British India

Application July 25, 1935, Serial No. 33,187
In Great Britain June 18, 1935

8 Claims. (Cl. 242—31)

This invention is for improvements in or relating to machines for winding yarn and the like on cops or bobbins. The object of the invention is to enable such a machine to be adjusted easily and quickly so as to wind cops or bobbins of different diameters, lengths and shapes.

According to the present invention, a winding machine comprises a traverse-rod having an extension on which the progression-wheel is mounted and means for adjusting the said extension laterally of the traverse-rod whereby the distance between the progression-wheel and the axis of the winding-spindle may be varied. The said means may comprise a pin-and-slot connection, more fully described below, between the traverse-rod and the said extension and an adjustable bracket for supporting the remote end of the extension.

According to another feature of the invention, the inner end of the said extension is slotted to receive within it a former-bar attached to the outer end of the traverse-rod and co-operating with the hub of the progression-wheel so as to build the heel of a cop on a plain tube. This former-bar takes the place of the usual external bar co-operating with a projection on the thread guide.

According to yet another feature of the invention, cam-mechanism is provided for reciprocating the traverse-bar with a varying speed of movement during each stroke. In this way, a firm non-shattering chase is obtained.

A specific embodiment of the present invention will now be described, by way of example, with reference to the accompanying drawings, in which:

Figures 1a and 1b show a plan of a winding-machine according to the invention with certain parts omitted;

Figures 2a and 2b show an elevation partly in section, of the machine shown in Figure 1;

Figure 3 is an elevation looking on the right-hand end of Figure 2;

Figure 4 is a section on the lines 4—4 of Figure 1b, and

Figure 5 is a section on the lines 5—5 of Figure 1b.

As shown in the drawings, the machine comprises a main frame 10 having bearings 11 for a tubular clutch-member 12 and a spindle 13 which lies within it. The tube 12 carries a grooved-wheel 14 which abuts against a spring 15, the other end of which engages a collar 16 affixed to the spindle 13. The worm 17 forms part of a tube which is also affixed to the spindle 13.

Rotatably mounted on the left-hand end of the spindle 13 is a pulley 19 having a conical face to co-operate with a clutch-member 20 formed integrally with the tube 12. The outer end of the

spindle 13 is supported in a bracket 21 (see also Figure 2).

The right-hand end of the tube 12 is formed with dogs 22 adapted to engage with corresponding slots in the collar 16 whereby a driving-connection is established between the tube 12 and the collar 16 so that when the clutch-member 20 is in frictional engagement with the pulley 19, rotation of the pulley drives the spindle.

The right-hand end of the spindle carries 10 spring-fingers 23 to engage the end 24 of a cop-holder; the other end 25 of the cop being supported by a centering-spindle 26 mounted in bearings in a plunger 27 pressed towards the cop by means of a spring 28 and slidable in a guide 29. 15 The plunger 27 terminates in a knob 30 whereby it may be retracted manually.

The worm 17 (see Figure 2) engages and drives a worm-wheel 31 having cut in its face a cam-track of two portions 32 and 33. The track is 20 engaged by a follower 34 on the shorter arm 35 of a bell-crank lever 35, 36, pivoted to the frame at 37. The arm 36 is pivoted to a link 38 which is in turn pivoted at 39 to a traverse-rod 40 25 slidable in a tubular guide 41 and in a bush 42.

The traverse-rod 40 carries a screw-threaded extension 43 pivotally attached to it as follows: As shown in Figures 1, 2 and 4, a former-bar 46, more fully described below, has a screw-threaded end 44 which engages the recessed end of the 30 traverse-rod 40 and is secured against rotation with respect thereto by a lock-nut 45. The screw-threaded extension 43 of the traverse-rod is slotted, as shown in Figure 2b, the former-bar 46 lying within this slot. The heel of the former-bar 46 is cut with a radial slot 47 through which passes a pin 48 carried on the screw-threaded portion 43. The pin 48 is engaged by a tension-spring 49, the other end of which engages a pillar 50 affixed to a bracket 51 on the former-bar, so 35 as to tend to move the screw-threaded portion downwardly, as seen in Figure 1. This tendency is resisted, however, by an adjusting-screw 52 passing through the bracket 51 and engaging with the enlarged head-portion 53 of the pin 48. 40 45

The other end of the screw-threaded rod 43 is mounted in a universal-joint 54 in a sleeve 55 which is attached by a screw 56 to a bracket 57 which is an extension from the main frame 10.

The screw-threaded rod 43 carries the usual 50 progression-wheel 58, the hub 59 of which is freely slidable along it, but which has a resilient wire 60 which passes through a slot in the hub into engagement with the screw-threads, so that the progression-wheel normally behaves as 55 though it were screw-threaded to the rod 43. In addition, the hub 59 carries the usual stirrup 61 to support the thread-guide 62 in the neighbourhood of the cop 63.

When it is required to build the cop 63 on a 60

plain cylindrical tube the parts are arranged as shown in the drawings, the progression-wheel 58 is moved to its extreme left-hand position (the spring 60 being released for this purpose) until 5 the hub 59 rides along the former-bar 46 and consequently pivots the screw-threaded rod 43 about 54, the pin 48 moving along the slot 47. It will be appreciated that the rod 43 now lies at 10 an oblique angle to the traverse-rod axis, having tilted about the joint 54. With the periphery of 15 the progression-wheel 58 just touching the bare cop-tube the machine is set in motion and winding commences. The spindle 13 rotates in the direction of the arrow shown in Figure 1 with 20 the result that the worm-wheel 31 is driven clockwise, as seen in Figure 2a. The shape of the cam-track 32, 33 causes the traverse-rod to be moved outwards comparatively quickly owing to the short and comparatively steep angle of the 25 spiral 33, but inwardly at a much slower rate of speed owing to the long gradual slope of the spiral 32. A further important point of design in the 30 cam-track is that each portion 32, 33 is somewhat steeper than a true Archimedean spiral, with the result that the speed of movement of the traverse-rod varies during each stroke. By this means it is 35 found that a firm non-shattering chase is obtained.

The progression-wheel acts, in known manner, 30 to advance the point of winding-on from left to right. As each chase is built up a point is reached at which the periphery of the wheel 58 makes contact with the wound-on yarn, with the result that the wheel is rotated and undergoes 35 a progressive movement to the right, whereupon a new chase is started. It will be seen that as the hub 59 of the progression-wheel travels to the right the spring 49 between the former-bar and the rod 43 asserts itself so as to move more and 40 more of the former-bar outwardly towards the position shown in Figure 1. As a result, the heel of the cop is given the desired tapering shape, as shown in the drawings, and as is obtained in 45 known manner by existing constructions of former-bar.

When the cop has been fully built the progression-wheel 58 engages with a bracket 64 carried on a rod 65, with the result that this rod is moved endwise and rotates a latch 66 (see Figure 2) 50 which normally holds a dog 67 attached to a bar 68. The bar 68 is engaged by a spring 69 attached to a collar 70 in such manner as to tend to rotate it inwardly so that when the dog 67 is released the bar rotates and the wedge-member 55 71 attached to a collar 72 on the rod engages the groove in the wheel 14, presses this wheel to the right against the pressure of the spring 15, releases the cone 20 from the pulley 19 and thus 60 interrupts the drive.

In the method of operation described above, 60 the screw 52 is set so that, after the progression-wheel 58 parts company with the former-bar 46 the screw-threaded rod 43 shall lie co-axial with the traverse-rod 40. However, the parts may be 65 differently arranged so as to give any desired shape to the heel of the cop. The parts may also be arranged so as to wind on a pирн a pre-formed conical end so as automatically to wind on the first sloping chase. This arrangement is achieved 70 as follows:

The spindle 13 is moved to the right with respect to the tubes 12, collar 16, and worm 17 by the release of appropriate grub-screws which are subsequently re-tightened. The extent of movement is such as to bring the point of commence-

ment of winding on the pирн opposite a point on the traverse-rod lying beyond the position on which the hub 59 of the progression-wheel parts company from the inclined edge of the former-bar 56. It will be seen that the diameter of the 5 finished bobbin depends on the distance of the screw-threaded rod 43 from the axis of the spindle 13 and the present invention enables this distance to be readily adjusted. First, the screw 52 is adjusted so as to bring the inner end of the 10 rod 43 to the desired position. If necessary, the nut 45 may be slackened off and the former-bar 46 rotated about its axis for this purpose. Thus, a wide range of different distances can be obtained. Next, the screw 56 which retains the 15 tubular support 55 is slackened off and this support may be rotated about the screw so as to bring the outer end of the rod 43 into line with the inner end so that the rod lies wholly parallel 20 with the spindle axis. If necessary, the former-bar may be rotated through 180° from the position shown in Figure 1.

In some cases it may be unnecessary to move the spindle 13, when winding on a cone-ended pирн, the former-bar being rotated about the 25 traverse-rod axis by a sufficient angular extent.

In order to enable the machine to be used for cops or bobbins of differing lengths the bracket 64 is adjustable endwise of the bar 68 so that the point at which the machine is stopped, as above 30 explained, may be adjusted.

By the present machine it is thus possible to wind cops of different diameters and different lengths and to wind on to a plain tube or on a cone-ended pирн. As shown in the drawings, the former-bar 36 has its profile slightly concave and it is found that it is still possible with such a profile to the heel of the cop to obtain a firm tight wind.

I claim:

1. In a winding machine for winding yarn or the like in conical chases, the combination comprising a traverse-rod, a slotted traverse-rod extension, a progression wheel having a hub mounted on said extension, and a former-bar carried by the traverse-rod and adapted to be received in the slot in the traverse-rod extension and formed with a wedging surface adapted to co-operate with the interior of the hub of the progression wheel to displace the traverse-rod extension laterally relatively to the traverse-rod at the commencement of the formation of a package to build the heel thereof.

2. In a winding machine for winding yarn or the like in conical chases, the combination comprising a winding spindle, a thread guide, a slotted rod disposed alongside the winding spindle, traversing means for causing relative reciprocation between the rod and the winding spindle longitudinally of the latter, a progression wheel cooperating with the thread guide and having a hub mounted on and in screw-threaded engagement with said rod and adapted progressively to displace the thread guide longitudinally thereof in accordance with the growth of the package, and a former-bar adapted to be received in the slot in said rod and having a face inclined to the direction of the length of the winding spindle and adapted to cooperate with the interior of the hub of the progression wheel to displace the rod towards the winding spindle at the commencement of the formation of a package to build the heel thereof.

3. In a winding machine for winding yarn or the like in conical chases, the combination com-

- prising a winding spindle, a thread guide, a slotted rod disposed alongside the winding spindle, traversing means for causing relative reciprocation between the rod and the winding spindle longitudinally of the latter, a progression wheel cooperating with the thread guide and having a hub mounted on and in screw-threaded engagement with said rod and adapted progressively to displace the thread guide longitudinally of the winding spindle and adapted to cooperate with 5 the interior of the hub of the progression wheel to displace the rod towards the winding spindle at the commencement of the formation of a package to build the heel thereof, and means for adjusting the said rod towards and away 10 from the winding spindle for winding packages of different diameters.
4. In a winding machine for winding yarn or the like in conical chases, the combination comprising a winding spindle, a thread guide, a slotted rod disposed alongside the winding spindle, traversing means for causing relative reciprocation between the rod and the winding spindle longitudinally of the latter, a progression wheel cooperating with the thread guide and 15 having a hub mounted on and in screw-threaded engagement with said rod and adapted progressively to displace the thread guide longitudinally thereof in accordance with the growth of the package, and a former-bar adapted to be received in the slot in said rod and having a face inclined to the direction of the length of the winding spindle and adapted to cooperate with 20 the interior of the hub of the progression wheel to displace the rod towards the winding spindle at the commencement of the formation of a package to build the heel thereof, and means for adjusting the said rod towards and away 25 from the winding spindle for winding packages of different diameters.
5. In a winding machine, the combination comprising a winding spindle, a thread guide, a traverse-rod for reciprocating the thread guide longitudinally of the winding spindle, a slotted traverse-rod extension, a progression wheel having a hub mounted on said extension, a former-bar carried by the traverse-rod and adapted to be received in a slot in the traverse-rod extension and formed with a face inclined to the axis of the traverse-rod and adapted to cooperate with the interior of the hub and of the progression wheel to displace the traverse-rod extension laterally relatively to the traverse-rod, and means 30 for adjusting the former-bar angularly about the axis of the traverse-rod.
6. In a winding machine, the combination comprising a traverse-rod, a slotted traverse-rod extension, a progression wheel having a hub mounted on and in screw-threaded engagement with said extension, a thread guide straddling the progression wheel, and a former-bar carried by the traverse rod and adapted to be received in the slot in the traverse-rod extension and formed 35 with a concave face inclined to the axis of the traverse-rod, which face is adapted to cooperate 40 with the interior of the hub of the progression wheel to displace the traverse-rod extension laterally relatively to the traverse-rod at the commencement of the formation of a package to build the heel thereof.

7. In a winding machine, the combination comprising a winding spindle, a thread guide, a traverse-rod for reciprocating the thread guide longitudinally of the winding spindle, a traverse-rod extension carrying said thread guide, 45 progression mechanism for advancing the thread guide step-by-step along the traverse-rod extension, said progression mechanism including a progression wheel having a hub mounted on said extension, a pin and slot connection coupling the traverse-rod and its extension together for endwise movement and permitting adjustment of the traverse-rod extension transversely of the traverse-rod towards and away from the winding spindle, a former-bar carried by the 50 traverse-rod, a cam face on the former-bar adapted to cooperate with the progression mechanism to displace the traverse-rod extension towards the winding spindle at the commencement of the formation of a package to build the heel 55 thereof, a bearing member for supporting that end of the traverse-rod extension which is remote from the traverse-rod, means for adjusting the traverse-rod extension transversely of the traverse-rod, said adjusting means including means for adjusting said bearing member both vertically and horizontally, means for mounting the former-bar and the pin and slot connection on the traverse-rod so as to be angularly adjustable about the axis of the traverse-rod 60 through a continuous range of settings, and means for securing the former-bar and the pin and slot connection to the traverse-rod in adjusted position.
8. In a winding machine, the combination comprising a winding spindle, a traverse-rod mounted for reciprocatory movement longitudinally of the winding spindle, a former-bar, means for mounting said former-bar on one end of the traverse-rod in alignment therewith and for angular adjustment about the axis of said rod, a traverse-rod extension, a pin and slot connection coupling the traverse-rod extension and the former-bar together for endwise movement and 65 permitting movement of the traverse-rod extension transversely of the former-bar towards and away from the winding spindle, a bearing member for supporting the end of the traverse-rod extension remote from the traverse-rod, a thread guide carried by said traverse-rod extension and adapted to reciprocate longitudinally of the spindle with the traverse-rod, progression mechanism for advancing the thread guide step-by-step along the traverse rod extension, said progression mechanism including a progression wheel having 70 a hub mounted on said extension and adapted, when near the end of said extension adjacent the traverse-rod, to cooperate with said former-bar to displace said traverse-rod extension towards the spindle, means for adjusting the end of the extension adjacent the traverse-rod transversely of the axis of the traverse-rod, and means for adjusting the bearing supporting the other end of the extension both horizontally and 75 vertically.

CHARLES MARSDEN.
